UNITED STATES PATENT OFFICE.

ADOLPHE VENNIN AND JEAN B. PELTIER, OF PARIS, FRANCE.

DESIGN FOR A GEM-SETTING.

SPECIFICATION forming part of Design No. 12,037, dated November 16, 1880.

Application filed October 28, 1880. Term of patent 7 years.

To all whom it may concern:

Be it known that we, ADOLPHE VENNIN and JEAN BAPTISTE PELTIER, citizens of France, residing at Paris, have invented and produced a new and original Design for Settings for Precious Stones, of which the following is a specification, reference being had to the accompanying drawings, forming part thereof.

Figure I is a side view of our newly-designed setting, and Fig. II a top view of the same.

The leading feature of our design consists in a double-gallery setting, the lower gallery consisting of a series of shell-shaped cups, and the upper gallery of diamond-shaped projections.

A are shell-shaped cups attached together to form a circle, and forming the lower gallery. At their point of connection diamond-

shaped projections B are made, turned upward, and forming the upper gallery or ring, and having corresponding diamond-shaped holes or openings C. The upper ends or points, a, are bent over the precious stone to secure the same to the setting.

25

We claim—
The design of a setting for precious stones, as herein shown and described, consisting of connected shell-shaped cups A, forming a lower ring or gallery, and diamond-shaped projections B, forming the upper circle or gallery.
